UNITED STATES PATENT OFFICE

YOSHI SHIMIZU, OF NEW YORK, N. Y.

SUBMARINE SIGNAL AND AIR-SUPPLY DEVICE

Application filed February 25, 1928. Serial No. 257,085.

This invention relates to submarine signalling devices, and particularly to an improved signalling device which is capable of presenting means whereby air or food may be supplied to sunken submarines.

Another object of the invention is to provide an attachment for submarines which is capable of presenting a signal at the surface when the submarine is submerged, whereby communication may be readily provided between the interior of the submarine and persons at the surface of the water.

A still further object of the invention is to provide for submarines not only a signalling device for indicating the location of a sunken submarine, but means whereby a cable or other elevating means may be connected to the submarine for lifting purposes.

In the accompanying drawings—

Figure 1 is a perspective view of a small part of a submarine illustrated as being below the surface, together with signalling means embodying the invention shown applied to the submarine.

Figure 2 is an enlarged sectional view through Figure 1, approximately on line 2—2.

Figure 3 is a fragmentary sectional view through Figure 1, approximately on line 3—3.

Figure 4 is a view similar to Figure 3, but with the parts arranged closed.

Figure 5 is an enlarged fragmentary perspective view of a cable guide embodying certain features of the invention.

Referring to the accompanying drawings by numerals, 1 indicates a submarine of any desired structure and to this submarine is connected certain parts hereinafter fully described which may be released from a point interiorly of the submarine, and when released will provide a signal at the surface of the water in case the submarine is submerged, and will also provide a communication between the parts above the water and the interior of the submarine. As indicated more particularly in Figure 3, a container or compartment 2 is secured to the submarine 1 and extends inwardly from the shell of the submarine. This compartment or container is closed except at the top and except at point 3 where a hose or pipe line 4 extends through

into the interior of the submarine. The upper part of the compartment or chamber 2 is in free communication with an enclosure 5 which is provided with a lid 6 having a suitable seal 7 in the nature of a gasket.

When the lid is closed as shown in Figure 4, all the parts therebeneath are in a watertight compartment and, therefore, will not be injured or brought into contact with the action of the sea water. The lid 6 is hingedly mounted at 8 and is provided preferably with a worm wheel 9 meshing with a worm 10. The worm 10 is connected with shaft 11 extending through a suitable packing box 12 and to a point interiorly of the submarine 65 where a hand wheel 13 is secured to the shaft. By this construction and arrangement, the lid 6 may be raised and lowered as desired. When lowered, the catch 14 may be actuated so as to interlock with the staple or loop member 15. Catch 14 is shaped like a bell crank lever and is connected to link 15 which extends to a point interiorly of the submarine where it is secured to an eccentric 16 actuated by handle 17. As soon as the lid 6 is closed, 70 handle 17 is swung from the position shown in Figure 3 to that shown in Figure 4. This will cause the eccentric 16 to prevent a return movement, and at the same time the hook 14 will be moved over to an interlocked position 75 in the member 15 and will also draw this member and part of the lid more tightly against the gasket 7. The parts remain in this position until the submarine, through some accident, becomes submerged and cannot rise. When this takes place, handle 17 is swung over to the position shown in Figure 3, whereupon the lid 6 is unlocked. Valve 18 is then opened. This valve is interposed 80 in pipe 19 which connects the interior of enclosure 5 with a point exteriorly of the submarine.

When valve 18 is opened as just described, water will flow into the enclosure 5 and chamber 2 so that the pressure interiorly and exteriorly of the lid 6 will be the same. As soon as this has taken place, hand wheel 13 is rotated and lid 6 is raised to the position shown for instance, in Figures 1 and 3. As soon as this takes place, the float 20 immedi-

ately moves upwardly until it assumes substantially the position shown in Figure 1. As it moves upwardly, the different parts associated therewith will gradually be drawn out and assume the position shown in Figure 1. Float 20 may be cork covered with canvas or any other desired structure, as for instance, a hollow metallic container. This float is provided with a number of braces 21 connected to a central hub 22. A spring 23 is connected to the outer ends of each of these braces and to the hollow standard 24 in any suitable manner through a ring structure 25. A spring 26 connects ring 25 with hub 22 as shown in Figures 1 and 2. By reason of this construction, the parts may be collapsed as shown in Figure 4, but when the lid 6 is raised, the parts will assume a vertical position as shown in Figure 1, and will remain in this position so that the lamp 27 may be seen from a distant point. Spring 26 is, of course, tubular in general formation so that cables 28 and 29 may extend therethrough and also pipes 30 and 31. These pipes are preferably flexible for the full length, though this is not essential provided they are flexible at the point they pass through the spring 26. Cable 28 provides a pair of wires connected to terminal 32 whereby telephonic communication may be secured between a vessel on the surface and a submerged submarine. The submerged submarine is provided with a telephone structure 33 of any desired kind and this is connected by cable 28 with the terminal 32. A vessel on the surface may have a telephone structure of any desired kind, and the wires may be plugged into the terminal 32 when the cap 34 has been removed. This cap is screwed into position and provides a water-tight connection by reason of the gasket 35. In this way, conversation may freely take place between those in the submarine and those on the surface. It will be understood that the members 28 to 31 inclusive, are all housed in a suitable flexible cable 36 which is clamped to the hub 22 by a suitable clamping ring 37 held in place by screws 38. The cable 29 carries preferably two insulated wires which supply electric current to the electric bulb or lamp 27, said current being supplied from a dynamo or suitable source of current in the submarine. A pipe or hose 36 extends through the hollow standard 34 and is connected with a sounding device 39, said sounding device being usually a whistle, though other forms of sounding devices could be provided. When air is forced through the tube 30, it will cause the sounding device 39 to function and thereby draw attention to the float 20 and associated devices. Pipe 31 is connected in any suitable manner with the hollow boss 40 whereby air or liquid food may be forced through this pipe into the submarine after cap 41 has been removed, said cap forming a water-tight clo-

sure in connection with the gasket 42. The cable 36 may be of any desired length, as for instance, two hundred or three hundred feet and extends from the hub 22 to the opening 3 through which it extends. Suitable packing is arranged around opening 3 so as to resist the water pressure. The various members 28 to 31 inclusive, after extending through opening 3, are extended to the proper place so that current may be supplied to the telephone device and to the lamp 27, while compressed air may be supplied to the whistle 39 and air from pipe 31 may be directed to different parts of the submerged submarine. Arranged in the compartment 2 is a guiding cone 43 around which the cable 36 is wound as shown in Figure 4. In order to prevent a proper unwinding without tangling, a guiding wheel 44 is rotatably mounted at the upper end of cone 43, said wheel having a turned over-edge flange 45 as shown in Figure 5. A ball 46 is loosely mounted in the flange 45 and from this ball a bar 47 extends, said bar merging into loop 48 through which cable 36 extends. As the cable is paid out, the wheel 44 rotates. A small cable 49 is connected to float 20 by a suitable eye member 50, said cable also passing over a pulley 51 connected to a yoke 52 which is fitted into the hook 53, said hook being rigidly secured to the submarine in any desired manner. The cable 49 is small and light, while pulley 51, yoke 52 and hook 53 are all heavy and strong. This structure is provided so that when a rescue ship is trying to raise the submarine, a heavy cable may be secured to the cable 49 and pulled downwardly and around pulley 51 and then upwardly. After this has been done, the heavy cable may be hoisted by the rescue ship, and by reason of the strong structure in members 51 to 53, the submarine may be properly raised to the surface of the water. By reason of this structure, it will not be necessary for a diver to go down to the submerged submarine as the heavy cable connection may be secured as just described, and then the lifting or hoisting operation performed. Only one of these devices is shown, but it will be evident that one, two or more may be provided for each submarine, and one or all may be released so that a number of hoisting cables may be secured to the submarine in order to secure a proper hoisting thereof.

What I claim is:

1. In a submarine signalling and air supply device, a float, a standard, bars connecting said standard with the float, said standard having a flexible section merging into a stiff hollow section, a plurality of springs connected with said standard and float whereby the standard may be folded against the float when in one position and caused by said springs to move to a position at right angles to the float when released, and a plu- 120 125 130

rality of communicating devices extending from said standard to a point interiorly of the submarine.

2. In a submarine signaling and air supply device, a float, a standard carried by said float, said standard having a flexible hollow section merging into a stiff hollow section, said flexible section acting to normally cause the standard to extend at right angles to the plane of the float, said flexible section permitting said standard to fold against the float, and a plurality of communicating devices extending through said standard to a point interiorly of the submarine.

15 3. In a submarine signaling and air supply device, a float, a framework connected to the float and arranged substantially in the plane of the float, said framework having a socket, a hollow standard formed with a 20 stiff tubular portion and a coiled wire tubular portion, one end of the coiled wire tubular portion being secured in said socket, said coiled wire tubular portion acting to normally hold the stiff tubular portion so that it 25 will extend at right angles to the plane of the float but will permit it to move to a position substantially parallel with the float, a plurality of coiling retractile springs connected to the float and to the standard at the 30 point where the coiled portion connects with the stiff portion, and a plurality of communicating devices extending through said standard to a point interiorly of the submarine.

35 Signed at New York city, in the county of New York and State of New York this 23rd day of February A. D. 1928.

YOSHI SHIMIZU.
